UNDERGARMENT

Frank A. Cohen, Brooklyn, N. Y.

Application February 15, 1946, Serial No. 647,948

1 Claim. (Cl. 2—38)

1

This invention relates to undergarments, and more particularly to that type of ladies' form-shaping and constricting garment known as a pantie girdle. Even more specifically, the invention pertains to pantie girdles of the "fig leaf" type wherein a wholly detachable crotch element defines the crotch of the undergarment and also comprises the inner side of each of the leg portions.

It is an object of my invention to provide an improved fig leaf pantie girdle in which the crotch element is attached to the girdle by fastening means whose individual elements are very closely spaced along the lateral edges of the crotch element, so that it is impossible under any circumstances for a wide gape to open between the girdle and crotch element while the undergarment is being worn, as is presently the case where the elements of the fastening means are remotely spaced.

It is a further object of my invention to provide an improved fig leaf pantie girdle of the character described in which the fastening means, notwithstanding the fact that its elements are very closely spaced, bends and twists with extreme readiness along the edges of the crotch element so that the undergarment loses none of its inherent flexibility.

It is another object of my invention to provide an improved fig leaf pantie girdle of the character described in which the fastening means when once closed will stay closed regardless of the activities of the wearer or long use of the fastening means, this being in contrast to the snap type fastener elements now used in many fig leaf pantie girdles.

It is an additional object of my invention to provide an improved fig leaf pantie girdle of the character described in which the fastening means, although of such nature that they will remain closed under any condition or manipulation save that intended to open them, nevertheless open very easily and quickly when desired, this being a marked improvement over the difficult-to-open hook type fasteners presently employed.

It is still another object of my invention to provide an improved fig leaf pantie girdle of the character described in which the fastening means is arranged in such fashion that the tender inner surface of the thighs is protected from chafing, pinching, abrasion, or scratching by said means, either when in closed condition or when opening or closing.

Other objects of my invention will in part be obvious and in part pointed out hereinafter.

The invention accordingly consists in the features of construction, combinations of elements,

2

and arrangement of parts which will be exemplified in the undergarments hereinafter described, and of which the scope of application will be indicated in the appended claim.

5 In the accompanying drawings, in which are shown various possible embodiments of my invention,

Fig. 1 is a three-quartered perspective view of a fig leaf pantie girdle embodying my invention as it appears when the crotch element is fully attached;

10 Fig. 2 is a similar fragmentary view of the girdle after the fastening means along one of the lateral edges of the crotch element has been opened;

15 Fig. 3 is a plan view of the crotch element as it appears when removed from the pantie girdle and laid on a flat surface;

20 Fig. 4 is an enlarged sectional view through the girdle as a fastening means, the same being taken substantially along the line 4—4 of Fig. 1; and

25 Fig. 5 is a view similar to Fig. 4 of a modified form of my invention.

Referring now to the drawings, and more particularly to Figs. 1—4, 10 denotes a pantie girdle embodying my invention. Said girdle is of approximately tubular shape and may be of any general construction well known to the art. Thus, the garment may include a plurality of vertically extending, circumferentially resilient panels 12, 14, 16, 18, 20, 22, secured together by rows of stitching 24 to provide a form shaping and constricting portion. It will be understood that this illustrated form shaping and constricting portion may be modified in many ways without affecting my invention. Thus, it may be knitted or woven as one piece, it may include or wholly consist of non-resilient material, it may include stays, gussets or laces, or it may have a vertical line of fastening elements to enable the garment to be 40 more easily taken on or off.

The pantie girdle also includes a crotch element 26. Although this element may be of any desired outline, I prefer to fashion it to a rectangular shape, as such shape lends itself best to the incorporation of fastening means pursuant to my invention. The element 26 should be of a soft, flexible fabric material, e. g. knitted rayon, in order to minimize chafing.

50 In girdles of the type under consideration, said crotch element is secured to the form shaping and constricting portion in some desired position, which will depend upon the design of the girdle and the purpose the girdle is intended to serve. As shown herein, by way of example, the crotch element is adapted to extend from the front to 55

the back of the girdle in the form of an arch, being connected to the front of the girdle along the edge of deep convex notch 28 and to the back of the girdle along a similar notch 30. Thus, the two lateral edges 32, 34 of the crotch element lie at the front and back of the girdle and the two ends 36, 38 of said element lie at the bottom of the girdle leg portions 40, 42.

The girdle and crotch element as thus far described are old, and it has been standard practice to detachably connect these members to each other, either by snap or hook fasteners. However, fasteners of such nature have several drawbacks when used for this purpose, and, as a result, the sales of fig leaf girdles have suffered materially. For example, snaps and hooks stiffen a rather considerable area of a fabric to which they are attached, so that if they are located close together a girdle becomes too stiff. On the other hand, if they are spaced apart appreciably, as is the custom, there is a tendency for the crotch element and form constricting portion to separate between the fastener elements in certain positions of the girdle. Furthermore, snap fasteners do not effect a secure closure and occasionally open accidentally, while hook fasteners, if the girdle is tight fitting, are very hard to open even when desired. In addition hooks and snap fasteners are comparatively bulky so that they disturb the smooth fit of outer garments and dig into the flesh.

Pursuant to my invention, all these drawbacks are avoided by employing slide fasteners 44 as the fastening means. The slide fastener at the front of the girdle includes two stringers 46, 48, one sewed along the edge of the front notch 28 and the other sewed along the lateral edge 34 of the crotch element. Each stringer comprises a conventional tape 50 having a beaded edge 52 along which a continuous closely and uniformly spaced series of individual standard slide fastener elements 54 are clinched. Said elements are provided with suitable interlocking means, e. g. a projection and underlying socket. A conventional camming slider 56 is used to guide the elements into interlocking or freed relationship. Desirably, said slider is of an automatically locking type, such for example as shown in U. S. Letters Patent No. 1,966,457, whereby it will remain in any position in which it is left. Each stringer 46, 48 has individual top stops 58 and the slide fastener has a separable bottom stop 60 of any well-known construction, for instance the pin and socket type such as shown in U. S. Letters Patent No. 1,842,045. Such arrangement permits the two stringers 46, 48 to be completely separated. The pin 62 of the bottom stop is located on the crotch element and the socket 64 on the girdle proper, thereby captively securing the slider 56 to the girdle where it is less likely to get lost or damaged, since the girdle is larger and less frequently laundered than the crotch element.

The slide fastener at the rear of the girdle is identical to that at the front although, if desired, it may, as shown, be oppositely disposed with regard to the direction of travel of the slider.

It is pointed out that the relatively tiny proportions of the slide fastener elements prevent them from noticeably stiffening the girdle, and their method of interlocking permits the slide 70 fasteners to be twisted and flexed as easily as the material of the girdle itself. Furthermore, the closures effected are continuous, thereby avoiding any possibility of gaps.

Pursuant to an ancillary feature of my inven-

tion, means are provided to protect the skin of a wearer from the slide fasteners. One such means is shown in detail in Fig. 4, where it will be seen to comprise two covering tapes 66, 68.

5 The covering tape 66 is secured by a row of stitching 70 along one of its longitudinal edges to the crotch element 26 in juxtaposition to the stringer 48, the tape being sufficiently wide to allow its free longitudinal edge to extend beyond the slide 10 fastener elements on said stringer. The other covering tape 68 is centrally longitudinally folded as at 72, and is secured by a row of stitching 74 running along said fold to the form constricting portion 10 in juxtaposition to the stringer 46. 15 The tape 68 is sufficiently wide to allow both its free longitudinal edges to extend beyond the slide fastener elements on the stringer 46. In operation the tape 66 will enter between the folded layers of the tape 68 and the overlapping tapes 20 will cover the slide fastener. Said tapes are disposed on the inner surface of the girdle and crotch element so that they will lie next to the skin of the wearer.

Desirably means also may be included to 25 detachably maintain the tapes in overlapping relationship initially, i. e. as the slider first starts to interlock the slide fastener elements. Such means includes a snap fastener the male element 76 of which is tacked, e. g. by stitching to one of 30 the tapes 66, and the female element 78 of which is attached to the other tape 68, preferably the layer closer to the slide fastener. Said means is located adjacent the separable bottom stop 60.

Another form of protecting means is shown in 35 Fig. 5. Said means differs from that shown in Fig. 4 only in that the tape 68 is not folded, and, accordingly is narrower. The several parts of this second protecting means are denoted by primed reference numerals which are otherwise the same 40 as the reference numerals used to indicate the same or similar parts in Fig. 4.

It will thus be seen that I have provided girdles which achieve the several objects of this invention and are well adapted to meet the conditions 45 of practical use.

As various possible embodiments might be made of the above invention, and as various changes might be made in the embodiments above set forth, it is to be understood that all matter 50 herein set forth or shown in the accompanying drawings is to be interpreted as illustrative and not in a limiting sense.

Having now described my invention, I claim 55 as new and desire to secure by Letters Patent:

A fig leaf pantie girdle comprising a tubular form shaping and constricting portion with a deep central convex notch at the lower edge of the front of said portion and a similar notch at the lower edge of the back of said portion, a crotch element of soft material adapted to extend from the front to the back of the girdle in the form of an arch at the crotch, with the opposite edges of the element at said notches, a pair of completely separable slide fasteners to connect the mentioned edges of said elements to the edges of said notches, each of said slide fasteners including a slider and a pair of stringers, one of the stringers being attached to the crotch element and the other to the form shaping and constricting portion, the sliders being captively secured to the form shaping and constricting portion, means to cover the surfaces of each of the slide fasteners at the inside of the girdle, said last named means including two pairs of overlapping tapes, one tape of each pair being

attached to the crotch element and the other tape of each pair being attached to the form shaping and constricting portion, both tapes of each pair being disposed alongside the associated slide fastener, and snap fastener means on tapes of each pair to detachably connect said tapes to one another, said snap fastener means being located adjacent the end of each slide fastener where interlocking starts.
